UNITED STATES PATENT OFFICE.

MAX R. LEHMAN, OF QUINCY, ILLINOIS, ASSIGNOR TO ORBON STOVE AND RANGE COMPANY, OF BELLEVILLE, ILLINOIS, A CORPORATION OF ILLINOIS.

DESIGN FOR A STOVE.

48,552.

Specification for Design.

Patented Feb. 15, 1916.

Application filed December 4, 1915. Serial No. 65,138. Term of patent 7 years.

To all whom it may concern:

Be it known that I, MAX R. LEHMAN, a citizen of the United States, residing at Quincy, in the county of Adams and State of Illinois, have invented a new, original, and ornamental Design for Stoves, of which the following is a specification, reference being had to the accompanying drawing, forming part thereof.

The figure is a perspective of a stove, showing my new design.

I claim:

The ornamental design for a stove, as shown.

MAX R. LEHMAN.

Witnesses:

JACOB R. WIBLE,
LOUIS LUDVIG.
